MACHINE FOR CUTTING PAPER OR THE LIKE

William Sargent, London, England

Application June 17, 1948, Serial No. 147,040

Term of patent 14 years

(Cl. D55—1)

To all whom it may concern:

Be it known that I, William Sargent, a subject of the King of Great Britain, residing at 18/20 York Buildings, Adelphi, London W:C.2., England, have invented a new, original, and ornamental Design for a Machine for Cutting Paper or the like, of which the following is a specification, reference being had to the accompanying drawings, forming part thereof.

Fig. 1 is a front perspective view of a machine for cutting paper or the like, showing my new design,

Fig. 2 is a top plan view,

Fig. 3 is a rear elevational view,

Fig. 4 is an elevational view of one end; and

Fig. 5 is an elevational view of the other end thereof.

I claim:

The ornamental design for a machine for cutting paper or the like, as shown.

WILLIAM SARGENT.
